(57) **CLAIM**

The ornamental design for an instrument display, as shown and described.

DESCRIPTION

FIG. 1 is a perspective view of an instrument display of my new design with accompanying instruments in phantom; FIG. 2 is a top plan view thereof, whereof a bottom plan view is a mirror image;

FIG. 3 is a left side elevational view thereof, whereof a right side elevational view is a mirror image;

FIG. 4 is a front side elevational view thereof; and,

FIG. 5 is a rear side elevational view thereof.

The broken line showing of environment is for illustrative purposes only and forms no part of the claimed design.
